UNITED STATES PATENT OFFICE.

HARRY H. HOFFMAN, OF BALTIMORE, MARYLAND.

WORK HOLDER.

1,403,781.

Specification of Letters Patent. Patented Jan. 17, 1922.

Application filed June 6, 1921. Serial No. 475,494.

To all whom it may concern:

Be it known that I, HARRY H. HOFFMAN, a citizen of the United States, residing at 4030 Hickory Ave., city of Baltimore, and 5 State of Maryland, have invented certain new and useful Improvements in Work Holders, of which the following is a specification.

This invention relates to work holders, 10 and especially to an improved handling device for faucets or spigots while buffing or otherwise operating on the spigots.

The main object of the invention is to provide a thoroughly practical, very efficient 15 and comparatively inexpensive device to which the spigots can be very quickly attached, which holds the spigots in such manner that nearly every part of its exterior surface is accessible to the buffing wheel, and 20 which, by a quick change of engagement with the spigot, enables the remaining part to be conveniently and safely held against the buffing wheel.

A further object of the invention is to 25 provide a work holder of this character which has interchangeable parts for fitting the chambers of different sized spigots, and other interchangeable parts for fitting spigot-shanks of different lengths.

30 A further object is to provide, in a device of this character, a simple and effective means to prevent rotation of the valve-handle while it is being buffed.

Other objects and advantages will be 35 pointed out or implied in the following details of description, in connection with the accompanying drawings in which,—

Fig. 1 is a side elevation of my improved work holder,

40 Fig. 2 is an edge view, or elevation at right angles to Fig. 1;

Fig. 3 is a view similar to Fig. 1, but showing a spigot held by the work holder,

45 Fig. 4 is a sectional view showing the internal threads for securing the interchangeable mandrels in place, and

Fig. 5 is a view illustrating several forms of interchangeable mandrels.

Referring to these drawings in detail, in 50 which similar reference characters correspond to similar parts throughout the several views, and in which a faucet or spigot of ordinary construction is shown at 8, to illustrate the application of the work holder, 55 the invention consists in the construction

and arrangement of elements which will now be fully described as follows:

A substantially cylindrical handle 1 is preferably spherical at its ends, as shown at 2, so that it can be conveniently rotated 60 about its cylinder-axis for turning the spigot while holding it against the buffing wheel. This handle is formed integrally or in one piece with a laterally extending arm 3 which has one side flush with one end of the handle. This arm includes a bifurcated free end portion 4 that is substantially parallel with and spaced from an axial extension 5, of the handle, which constitutes a mandrel for extending into the chamber or passage 70 in the attaching end of the faucet or spigot to be operated upon. For convenience in fitting this device to faucets of different sizes, and having passages of different diameters, I may provide a number of interchangeable mandrels 5, 5^a, 5^b, and probably others; these mandrels having threaded shanks of a uniform size and threading, so that they can be fitted alternatively into the threaded bore 6 of the handle 1. Instead 80 of threading the interchangeable mandrels into the handle 1, I may secure them in the handle by frictional engagement or by other appropriate means; or, as a simple form of the device, I may form any one of them 85 integrally with the handle. At the opposite end of the handle is a supplemental mandrel 7 which may be of any appropriate diameter and shape, or may be interchangeable with the mandrels 5, 5^a, 5^b, etc., or 90 formed integrally with the handle.

The furcations 8 of the arm 4 are spaced just enough to permit the easy entrance of the valve-shank of the spigot, as shown, and a pin or stud 9 extends laterally from the arm 95 or bifurcated extension at a position in which it abuts against the valve-handle of the spigot to prevent turning of the handle while it is being buffed. This stud or abutment 9 is especially useful in preventing 100 wheellike handles from turning, as it extends between the spokes of the wheel or handle and limits the rotation in either direction. These studs may be removable, as indicated in Fig. 4, or they may be formed 105 integrally with the arm 4.

In order that this work holder may be interchanged to hold long-shank spigots as well as the short-shank spigot here shown, I may provide a bifurcated extension or at- 110

tachment 10 with a shank 11 of a size to snugly fit between the furcations 8, and I may secure this attachment in place by any appropriate means, for instance, a taper-pin 5 12 to fit in registering apertures 13 and 14 of the two bifurcated elements. When the element 10 is attached to the element 4, the furcations 8^a engage with the valve-shank of the long-shank spigot while the adjacent 10 mandrel is inserted in the chamber of the long attaching shank of the spigot.

While this work holder can be used in different ways, the following will probably be preferable: The valve of the spigot is first 15 tightened to hold the valve-handle against turning while it is being buffed on the side that will be next to the stud 9, and while the valve stem and upper rear part of the spigot is being buffed. After this much of the 20 buffing is completed, the heat of friction is so great that it is difficult to hold the polished or buffed parts with the naked hand, and ordinarily, the spigots are left to cool while others are being similarly partly 25 buffed; but by use of this holder, the buffing can be completed without laying the spigot aside to cool, and it is now placed in the holder as shown, and the unpolished or unbuffed parts are accessible by the buffing 30 wheel while the handle 1 protects the hands of the operator from the heat-of-friction while providing a positive means of supporting and quickly and evenly turning the spigot while holding it against the buffing 35 wheel. It should be understood that the mandrel 7 is for inserting in the chamber of the spigot while the parts are being buffed which are rendered inaccessible to the buffing wheel by the bifurcated arm 4 or its attachment 10.

The mandrels are preferably slabbed or

planed at 15 for engagement with a wrench for loosening and tightening them in the handle 1.

It is not intended to limit this invention to 45 the exact details of construction and arrangement shown, but changes may be made within the scope of the inventive ideas as described and claimed.

What I claim as my invention is: 50

1. In a work holder, the combination of a substantially cylindrical handle, a mandrel extending in axial alignment with said handle, and an arm formed integrally with said handle and extending laterally from one 55 end of the handle, said arm including a bifurcated extension that is spaced from and substantially parallel with said mandrel, the space between the furcations of said arm being in position to receive the valve-shank 60 of a spigot when said mandrel is inserted in the hollow shank of the spigot.

2. The structure defined by claim 1, said bifurcated extension being provided with an abutment to engage the valve-handle of the 65 spigot and prevent rotation of the handle.

3. The structure defined by claim 1, an auxiliary bifurcated extension of the first said bifurcated extension being provided and having a shank adapted to fit snugly 70 between the furcations of the first said extension, and means to removably secure said shank to said furcations.

4. The structure defined by claim 1, and a mandrel extending axially from the other 75 end of the handle.

5. The structure defined by claim 1, said mandrel being interchangeable with other mandrels, for the purpose specified.

In testimony whereof I affix my signature. 80

HARRY H. HOFFMAN.
